United States Patent Office.

HARRY S. GRIFFITHS, OF BROOKLYN, NEW YORK.

Letters Patent No. 77,482, dated May 5, 1868.

IMPROVEMENT IN SUSPENSION-RINGS.

The Schedule referred to in these Letters Patent and making part of the same.

TO ALL WHOM IT MAY CONCERN:

Be it known that I, HARRY S. GRIFFITHS, of Brooklyn, in the county of Kings, and State of New York, have invented a new and improved Suspension-Ring for business-cards; and I do hereby declare that the following is a full, clear, and exact description thereof, which will enable others skilled in the art to make and use the same, reference being had to the accompanying plate of drawings, and to the letters of reference marked thereon, forming part of this specification.

Figure 1 represents my improved device of a suspension-ring attached to a card to suspend it.

Figure 2 represents the same detached, before the fastening-spurs are bent.

Figure 3 represents the same attached to a card, with one of the fastening-spurs closed down.

Figure 4 represents a perspective view when ready for use.

Similar letters of reference indicate corresponding parts.

This invention relates to a new and useful device for attaching to business-cards, by which they may be conveniently suspended against a wall for display and preservation.

The common method of hanging or suspending unframed business or show-cards for display is to tack them against a wall, by which the cards are injured and the wall defaced, so that there is often objection made to placing them where they can be observed.

My invention is designed to obviate this difficulty attending the display and preservation of business and show-cards, and it is accomplished by a very cheap and simple device, consisting of a ring with spurs, which is stamped out of thin sheet metal, the spurs being inserted and fastened in the edge of a card centrally, and the ring hung on a nail or pin against the wall, as shown in fig. 1.

A thin sheet of brass, or other suitable metal, is stamped or struck up with a die, forming a ring, *a*, with a side-piece, *b*, provided with spurs, *c c*, bent at the sides, to be inserted through the edge of a card, and turned down on the opposite side to secure them to the card.

The metal may be embossed or struck up in any ornamental design for the fastener.

Having thus described my invention, I claim as new, and desire to secure by Letters Patent—

The suspension-ring for business-cards, constructed and employed substantially as and for the purpose herein described.

HARRY S. GRIFFITHS.
